UNITED STATES PATENT OFFICE

GEORGE WARREN DREW, OF OAKLAND, CALIFORNIA

FIRE-DOOR-CONTROLLING MECHANISM

Application filed May 28, 1927. Serial No. 195,014.

My invention forming the subject matter of this application is controlling mechanism for rolling fire door.

An object of this invention is to provide a device which in case of fire is operated by the heat of the fire to lower the rolling door and separate the compartment on fire, from the other compartments or rooms of the building.

Another object of this invention is to provide a fire door which when closed is still sufficiently resilient to be readily opened by a person trying to escape from the compartment.

The above and other objects in view will readily appear as the description proceeds.

Although I have described an embodiment of my device considered to be the best, it is to be understood that changes may be made in the design and arrangement of parts within the scope of the claims without departing from the spirit or sacrificing the advantages of the invention.

In the accompanying one-sheet of drawing: Figure 1 is an end view of the device.

Figure 2 is a cross section taken along the line 2—2 of Figure 1.

Figure 3 is a sectional view taken along line 3—3 of Figure 2.

Figure 4 is an end elevation showing the rolling fire door attached to the device.

Figure 5 is a detail sectional view taken on the line 5—5 of Figure 3.

A roller fire door 1 made of fire proof material extends across the exit of a compartment and is guided by the grooves 2 disposed in the walls of the building. The free bottom of the door 1 is slidable in the grooves 2, the other end of the door is attached to the outside periphery of discs 2' oppositely disposed at both sides of said door, the sides of said door extending over drums 3. The disc 2' is fixedly secured to a spindle 4, said spindle in turn is rotatably supported in a bracket 5 in a manner to be hereinafter described. The drum 3 is rotatable on the spindle 4. A coil

spring 6 is disposed in the drum 3, one end of said spring being anchored to the spindle 4 as at 7, the other end thereof being secured to the drum 3 as at 8. A bearing 8' is rotatably supported in the bracket 5 and extends therethrough. The spindle 4 is rotatable in said bearing. A ratchet 9 is fixedly secured to the other end of the bearing 8'. A spiral groove or track 10 is disposed on a face of said ratchet. The spiral groove 10 as shown in Figure 3 is cut to a length to permit the ratchet to rotate approximately two and a half turns, but it is understood that the groove could be cut to any length and number of turns. The ends 11 of the spiral groove are adapted to abut against a traveler 12 slidably disposed in a pocket 13 on the bracket 5, thereby allowing the traveler 12 to slide radially in the pocket 13 but preventing the rotation thereof with the groove 10, the rotation of the ratchet is limited by the ends 11 of the groove 10 which abuts against the traveler 12. A pawl 14 is pivoted at 15 to the bracket 5 and engages the ratchet, said pawl 14 is held in engagement with the ratchet 9 by means of a lever 16 pivotally secured to the bracket 5 at 17. The arm 18 of the lever 16 is long enough to be turned by gravity outwardly from the bracket 5, around the pivot point 17. The portion 18 of the lever 16 is connected to a flexible line 19 having fusible joints 20 thereon. The pockets 21 are disposed around the face of the ratchet 9 in order to provide sufficient space for a lever or a bar by means of which the ratchet 9 is manually rotated for the purpose to be hereinafter described.

The invention operates as follows: The drawing illustrates the device in a position ready to be lowered by the action of the heat produced by a fire. The flexible line extends over the whole compartment or the whole building and the fusible joints 20 are spacedly disposed therebetween. In case of fire at any point the nearest fuse 20 thereto

melts and breaks the connection between the sections of the line 19. When the tension of the flexible line 19 is released the lever 16 swings outwardly around the pivot 17 on account of the weight of the portion 18, thereby releasing the pawl 14 and disengaging the same from the ratchet 9. The weight of the door rotates the disc 2' and the spindle 4 therewith, which in turn rotates the drum 3 by means of the coil spring 6. The drum 3 rotates as a unit with the bearing 8' and the ratchet 9 thereon. The traveler 12 stops the movement of the ratchet 9, thereby preventing any further rotation of the bearing 8' and drum 3 by the unrolling door 1.

The further downward movement of the door rotates the discs 2' and the spindle 4 in the bearing 8' against the tension of the coil spring 6 thereby unwinding about one-fourth of the total tension of said coil spring 6, so that when the door is completely closed the coil spring still retains about three-fourths of the originally fully wound tension thereof in order to counter-balance the weight of the door 1 and thereby to facilitate the raising thereof, but said three-fourths spring tension is not enough to hold the door 1 in an up raised position. If anyone is caught in the fire and tries to escape through the exit it is only necessary to exert a very little upward force on the door 1 because the weight of the door is almost completely counter-balanced by the remaining tension of the spring 6 and it renders great assistance in raising the door rapidly and permits a person to leave the room, but as it has not sufficient tension left therein to support the door in an upraised position after released the door automatically lowers again.

When the fire is over and the door must be opened, it is raised to the highest elevated position and is held there until the pawl is engaged in the ratchet and the fuse is replaced on the flexible line 19 thereby forcing the lever 16 under the pawl 14 and securing the same in its locked position, a lever or bar is then placed into one of the pockets 21 and the ratchet is rotated thereby in order to wind the spring. The spring is wound until the tension thereof is sufficient to support the door 1 in the elevated position thereon. The tension of the spring 6 and the number of turns or revolutions by the ratchet 9 and the track 10 before the end 11 abuts the traveler 12 is adjustable by the number of turns used when the spring 6 is wound by the ratchet. The position of the traveler 12 in the bracket 10 relatively to the track end 11 determines the number of turns or revolutions the ratchet rotates before the door is lowered, thereby providing ready means to adjust the tension of the spring.

The traveler 12 is so disposed relatively to the track end 11 that it permits the turning 65 of the ratchet 9 just far enough to reduce the

tension of the spring by the one-fourth thereof, about three-fourths of the full wound spring tension is left therein after the door is lowered in order to help to raise the door. When the spring is wound again by the ratchet 9 the ratchet is turned around only far enough to regain the unwound one-fourth spring tension therein, thereby placing the traveler 12 in the relative position to the end 11 occupied before the fire started.

Claims:

1. In a fire door controlling mechanism, a drum, a spindle rotatable in said drum and adapted to roll and unroll the fire door, a spring securing said spindle to said drum, means to wind said spring, means to limit the unwinding of said spring when the fire door is lowered and to retain sufficient tension therein to aid in raising the same.

2. In a fire door controlling mechanism a drum, a spindle adapted to roll and unroll said fire door, said drum being rotatably positioned, on the spindle, a spring anchored to said spindle and in said drum, means to rotate said drum thereby to wind said spring, means to limit the unwinding of said spring when the fire door is lowered and to retain sufficient tension therein to assist in raising the same.

3. In a fire door controlling mechanism as claimed in claim 2, said limiting means comprising a spiral track on the winding means, and a stop adapted to travel on said track and limit the rotation of said winding and unwinding means.

4. A fire door controlling mechanism comprising a drum, a spindle, a rolling fire door secured thereto, a coil spring anchored to the spindle and to the drum, means to wind said spring, means to hold said spring in wound position, and means to release a part of the tension thereof; said releasing means comprising a ratchet secured to said drum, having a spiral groove on one face thereof, a stop adapted to travel in said groove and to limit the movement of said ratchet, and fusible means to release said ratchet.

5. A fire door control mechanism comprising a spindle, a disc fixedly secured thereto, a rolling fire door on the disc; a drum rotatably positioned on the spindle, a spring secured to the shaft and to the drum; means to rotate the drum for winding the spring, means for arresting said winding means in the wound position of the spring; and limiting means to allow the unwinding of a part of the tension of the spring when said arresting means is released.

6. A fire door control mechanism comprising a spindle, a disc fixedly secured thereto, a rolling fire door on the disc; a drum rotatably positioned on the spindle, a spring secured to the shaft and to the drum; means to rotate the drum for winding the spring, means for arresting said winding means in the wound position of the spring; and limit-
